(57) **CLAIM**

The ornamental design for a soap dish, as shown and described.

DESCRIPTION

FIG. 1 is a perspective view of a soap dish showing our new design;

FIG. 2 is a front elevational view;

FIG. 3 is a rear elevational view;

FIG. 4 is a side elevational view;

FIG. 5 is a side elevational view;

FIG. 6 is a top plan view; and,

FIG. 7 is a bottom plan view.

The broken line disclosures in the views represent portions of the soap dish in which the claimed design is embodied, but which forms no part of the claimed design.
